UNITED STATES PATENT OFFICE.

GARTH GRIFFITH GILPIN, OF RIVERSIDE, ILLINOIS, ASSIGNOR TO WALTER P. MURPHY, OF CHICAGO, ILLINOIS.

RELEASE-RIGGING.

1,290,969.

Specification of Letters Patent. Patented Jan. 14, 1919.

Application filed December 17, 1915. Serial No. 67,403.

To all whom it may concern:

Be it known that I, GARTH G. GILPIN, a citizen of the United States, residing at Riverside, in the county of Cook and State of Illinois, have invented certain new and useful Improvements in Release-Rigging, of which the following is a specification.

My invention relates to apparatus for drawing the locking pins, or equivalent elements, of car couplers, apparatuses of this sort being commonly called release riggings or uncoupling mechanisms.

One of the objects of the invention is to provide a release rigging which will be simple in its construction, effective and positive in operation, and which will consist of a few strong and durable parts so that the device will be capable of withstanding the rough usage to which everything connected with a railway freight car is subjected.

A further object of the invention is to provide certain devices whereby release riggings of the chain type may be conveniently and economically reconstructed so that a rigid link, having connections sufficiently flexible with the operating rod of the uncoupling device and with the coupler to permit the free movements of the latter, may be substituted for the chains heretofore used in a certain well known type of uncoupling mechanism. This type of apparatus consists of a cranked rod revolvably mounted on the end of the car, the crank of which is connected by a chain and clevises to the locking pin of the coupler. The use of chains and clevises in this situation is objectionable, for reasons which are well understood; and uncoupling riggings of this type have been generally condemned, and their use by the railroads is being to a large extent abandoned. As there are a great many railway cars equipped with these apparatuses, it is desirable for economical reasons to utilize the old equipment so far as possible. My invention provides means for accom-
ishing this reconstruction of the old apparatus at a minimum of cost for material and labor.

A further object of the invention is to provide a novel form of bracket for supporting the operating rod of an uncoupling device which permits the ready removal of the rod therefrom without, however, disengaging the movable part of the bracket from

the fixed member thereof. This arrangement is a convenience as it obviates the danger of losing any part of the bracket when the uncoupling rod is removed for the purpose, for example, of disengaging the device from the locking pin of the coupler when the coupler is taken off the car for repair or replacement.

The invention consists of the novel constructions, arrangements and devices to be hereinafter described and claimed for carrying out the above stated objects, and such other objects as will appear from the following description. The invention, however, is not to be understood as limited to the exact construction and arrangement of the parts shown except so far as certain of the claims hereto appended are specifically so limited.

The invention is illustrated, in certain preferred embodiments, in the accompanying drawings in which—

Figure 1 is a fragmentary view, in perspective, of the end sill and coupler of a railway car with the uncoupling mechanism of my invention applied thereto.

Fig. 2 is a fragmentary side view of the crank portion of the operating rod together with the casting secured thereto for maintaining the engagement between the rod and the link which connects the locking pin of the coupler with the rod.

Fig. 3 is a plan view of the parts shown in Fig. 2.

Figs. 4 and 5 are views, in elevation, at right angles to each other, of the connecting link.

Fig. 6 is a perspective view of a preferred form of bracket for supporting the operating rod.

Fig. 7 is a similar view showing the bracket opened so that the uncoupling rod may be removed therefrom.

Fig. 8 is a view similar to Fig. 1 showing a modified construction of the supplemental casting on the end of the crank of the operating rod, and

Fig. 9 is a detail perspective of this casting.

Like characters of reference designate like parts in the several figures of the drawings.

Referring first to Figs. 1 to 7 inclusive, 105 10 represents the end sill of the car, 11 the dead wood and 12 the coupler, which latter may be of any preferred type. The lock-

ing pin of the coupler is shown at 13 and is formed with the usual eye 14. 15 is the operating rod of the release rigging formed at one end with a handle 16 and at the other with a crank 17. In the chain type of uncoupling mechanism referred to above, the crank of the uncoupling rod is connected to the locking pin of the coupler by means of a chain and clevises, the end of the crank being flattened, as shown at 18, and formed with a perforation 19 for the bolt of the upper clevis. A clevis connection in a situation of this sort is objectionable because the nut on the bolt may easily be lost. Furthermore, when the coupler is repaired the repair man replacing it on the car may forget to connect the clevis or may lose the bolt which is taken out when the clevis is disconnected for the purpose of removing the coupler. The chain connection is particularly objectionable because it is likely to become kinked and thereby, in effect, shortened, with the result that the locking pin of the coupler is accidentally pulled by a normal outward movement of the coupler.

My invention utilizes, in place of the chain, a rigid link 20 formed preferably with an open spirally formed hook 21 at its lower end engaging the eye 14 of the unlatching pin and with a closed loop 22 through which the crank of the operating rod extends. To maintain the connection between the crank and the link I provide a casting 23 formed with stop shoulders 24 and with a slot 25. The casting is secured to the end of the crank by a rivet 26, or other suitable fastening means, which extends through the perforation 19 in the crank formerly used for the upper clevis link.

The arrangement shown in Figs. 8 and 9 is the same as that shown in the preceding figures except that the casting 23^a is provided with another pair of stop shoulders 27 on the other side of the loop 22 of the link.

It will be seen that the link has considerable freedom of movement with respect to the crank of the operating rod. It will slide freely up and down to accommodate for the vertical movements of the coupler. It is capable also of a certain amount of angular movement on the crank to permit the forward and backward movements of the coupler. The loop 22 is of a sufficient width so that the coupler is not impeded in its normal lateral movements. However, the link is not, in the preferred form of my invention, capable of axial rotation. For this reason it is possible to use an open hook for making the connection between the link and the eye of the coupler pin without danger that the parts will be disengaged by the movements of the coupler in drawing, buffing, or rounding curves, for instance. The

connection is made quite safe if the hook be given the spiral shape shown in the drawings.

The use of an open hook in this connection permits the disconnection of the link 70 from the locking pin of the coupler when the coupler is to be repaired or replaced, provided, however, that the operating rod is removed from its supports on the car.

These supports may consist of any ordinary brackets used in apparatus of this sort but I prefer to employ the special form of bracket shown in the drawings. The center bracket, for example, consists of a strip of metal 28 bent so as to form an upper flange 80 29 and a lower flange 30, the latter formed preferably with an upturned lip 31; and of a channel-shaped closure piece 32 which fits within the flange 30, 31 of the bracket, and is provided with a shank 33 extending through an opening 34 in the upper flange 29. The upper end of the shank is preferably bent over at 35 to form a stop. The operating rod 15 rests in the closure piece, as shown in Fig. 6, when the rod is in operative position. When the rod is to be removed it and the closure piece are raised and the latter is turned to the position shown in Fig. 7.

The end bracket 36 may be identical in 95 construction with the center bracket just described. Preferably, however, it is provided with an angular stop flange 37 for the handle 16 of the operating rod.

When brackets of the sort above described 100 are employed the rod may be demounted from the car very expeditiously and without the removal of any parts, such as bolts or cotters, which are likely to become lost. When the rod has been demounted the hook 21 can be disengaged from the eye of the locking pin. The link does not have to be removed from the operating rod so that the release rigging, when taken from the car, can be handled as a unit. If a coupler 105 is to be repaired it is, however, necessary for the repairman to demount the rod, since the shape of hook 21 is preferably such that the link cannot be disengaged from the coupler with the rod on the car. If the whole 110 release rigging has to be taken from the car when the coupler is removed the chances are that it will be put back on the car when the coupler is replaced. A clevis connection is very easily forgotten. If the hook at the lower end of the link were formed so that it could be detached from its locking pin conditions might arise causing this disengagement accidentally. The apparatus employs no clevises, bolts or devices of that 115 sort. The connection between the operating rod and the locking pin of the coupler consists of a single rigid link having a permanent engagement with the operating rod and a simple hook engagement with the locking

pin. These engagements are sufficiently flexible for all movements of the coupler. At the same time they are positive so that as long as the operating rod is in its normal 5 position there can be no disengagement as between the uncoupling rigging and the locking pin of the coupler.

It will be understood that the locking pin is drawn by lifting on handle 16 of the operating rod. When the pin is in lock set position the rod will return to its normal position, as shown in Fig. 8. If the draw-bar of the coupler or its attachments should fail the connection between the operating 15 rod and the locking pin is such that the latter will be automatically withdrawn so as to uncouple the car from the adjacent car of the train.

I claim:

- 20 1. A release rigging comprising an operating rod revolvably supported on the car and formed with a crank, a rigid link adapted for engagement with the locking pin of the coupler and provided at its upper end 25 with a loop through which said crank projects, and a separately formed member secured to the crank for maintaining an operative engagement between the link and crank.
- 30 2. A release rigging comprising an operating rod revolvably supported on a car and provided with a crank formed with an eye, a rigid link for connecting the locking pin of the coupler with said crank, and a separately formed member secured to said crank through the eye providing a means of connection between the link and crank which permits vertical and angular movement of the link relative to the crank.
- 35 3. A release rigging comprising an operating rod revolvably supported on the car and provided with a crank formed with an eye, a rigid link having an open hook at its lower end for engagement with the locking 40 pin of the coupler, and a separately formed member secured to said crank through said eye providing a means of connection between the link and crank which permits vertical and angular movement of the link relative to the crank.
- 45 4. A release rigging comprising an operating rod revolvably supported on the car and provided with a crank formed with an eye, a rigid link having an open hook at its lower end for engagement with the locking 50 pin of the coupler and formed at the upper end with a loop through which said crank extends, and a separately formed member secured to said crank through the eye for maintaining an operative engagement between the crank and link.

55 5. A release rigging comprising an operating rod revolvably supported on the car and provided with a crank formed with an

eye, a rigid link having an open hook at its lower end for engagement with the locking pin of the coupler and formed at the upper end with a loop through which said crank extends, and a separately formed member secured to said crank formed with spaced stop shoulders on opposite sides of said loop. 70

6. A release rigging comprising an operating rod formed with a crank, supporting brackets on the car having movable closure elements to permit the removal of the rod from said brackets, a rigid link having an open hook at its lower end adapted to be freely engageable with the locking pin of the coupler when one of said elements is detached from the car, and a separately formed member secured to said crank providing a flexible operative connection between the link and crank. 75

7. A release rigging comprising an operating rod revolvably supported on the car and formed with a crank, and a rigid link having a flexible connection with the locking pin of the coupler and provided at its upper end with a loop lying in a plane substantially at right angles to the axis of the car and extending around the end of the crank and slidably longitudinally therein; said crank being provided with means for maintaining the loop of the link in engagement therewith. 80

8. A release rigging comprising an operating rod revolvably supported on the car and formed with a crank, and a rigid link having a flexible connection with the locking pin of the coupler and provided at its upper end with a loop extending around the end of the crank and slidably longitudinally thereon; said crank being provided with spaced stop shoulders which stand on opposite sides of said loop. 95

9. A release rigging comprising an operating rod having a crank, means for revolvably supporting the same on a car, a link provided at one end with an open hook adapted for engagement with the coupler lock, a separately formed member secured to the crank, and means on said link whereby the link is connected with said member so that it is non-revolute about its longitudinal axis when said coupler and crank are in operative position. 100

10. A release rigging, an operating rod having a crank, means for revolvably supporting the same on a car, a link provided at one end with an open hook adapted for engagement with the coupler lock and at the other end with a loop, and a separately formed member secured to said crank which extends loosely through said loop and is provided at its outer end with a stop to prevent the loop from becoming disengaged therefrom. 115

11. A release rigging comprising an operating rod having a crank, means for revolu- 120

125

- bly supporting the same on a car, a link provided at one end with an open hook adapted for engagement with the coupler lock and at the other end with an elongated loop, and 5 means for preventing axial rotation of said link comprising a separately formed member secured to said crank which extends through said loop and is provided at its outer end with a pair of stops on opposite 10 sides of said loop.
12. A release rigging comprising an operating rod having a crank, means for revolving the same on a car, a link provided at one end with means for engaging 15 a coupler lock and at the other end with a

loop, and a separately formed member secured to said crank which extends through said loop and is provided at its outer end with a pair of stops on opposite sides of said loop.

13. A release rigging comprising an operating rod revolvably supported on the car and formed with a crank, a rigid link adapted for engagement with the locking pin of the coupler and provided at its upper end with a loop through which said crank projects, and a separately formed member secured to the crank, having spaced stop shoulder on opposite sides of said loop.

GARTH GRIFFITH GILPIN.
